UNITED STATES PATENT OFFICE

2,173,800

VIOLIN PEG

Raymond Coates, Port Allen, La., assignor of one-half to Joseph G. Dubois, Baton Rouge, La.

Application February 24, 1939, Serial No. 258,273

2 Claims. (Cl. 84—305)

This invention relates to violin pegs and has for an object to provide a peg which will permit a violin string being attached and tensioned in much less time than heretofore possible.

5 A further object is to provide a peg having a shank split longitudinally to provide resilient shank portions adapted to clamp the violin string between them.

A further object is to provide a peg of this 10 character which will be formed of a few strong, simple and durable parts, which will be inexpensive to manufacture, and which will not easily get out of order.

With the above and other objects in view the 15 invention consists of certain novel details of construction and combinations of parts hereinafter fully described and claimed, it being understood that various modifications may be resorted to within the scope of the appended claims without 20 departing from the spirit or sacrificing any of the advantages of the invention.

In the accompanying drawing forming part of this specification,

Figure 1 is a plan view, with parts broken 25 away, of the portion of the violin head showing pegs constructed in accordance with the invention applied thereto.

Figure 2 is a plan view of one of the pegs in applied position.

30 Figure 3 is a fragmentary plan view showing the initial stage of application of a violin string to the peg.

Figure 4 is a fragmentary plan view showing the final stage of application of a violin string 35 to the peg.

Figure 5 is an end elevation of the foot piece of the peg.

Figure 6 is an end elevation of the peg.

Referring now to the drawing in which like 40 characters of reference designate similar parts in the various views, the peg is shown to comprise a shank formed of metal bent to provide a loop 10 and substantially straight, slightly divergent shank portions 11. The loop and parts 45 of the shank portions are embedded in the head 12 and tapered shank 13 of the peg and for this purpose the head and shank may be formed of two symmetrical parts recessed to receive the

loop and shank portions 10 and 11 between them, as shown in Figures 2 and 6.

A tapered tubular foot piece 14 is provided, the same being provided with a metal lining 15 which is provided with a beveled guide 16 to facilitate entrance of the leading ends of the shank portions 11 of the peg, these leading ends being pointed out as shown in 17. The foot piece is adapted to be inserted in an opening 18 in one of the sides of the violin head 19 while the tapered shank 13 of the peg is adapted to be inserted in an opening 20 formed in the other side of the head in alignment with the opening 18.

In operation the violin string 21 is inserted at one end in the space between the shank portions 11 of the peg, after the shank 13 of the peg is pulled out of its opening 20 sufficiently to permit the resilient shank portions 11 to almost clear the lining of the foot piece as shown in Figure 3. Then the peg is pushed inwardly to 20 force the shank portions 11 through the lining 16 of the foot piece, as shown in Figure 2, in which position the resilient shank portions are tightly clamped against the violin string 21 and hold the clamped end stationary so that the 25 string may be quickly tensioned and tuned.

From the above description it is thought that the construction and operation of the invention will be fully understood without further explanation.

What is claimed is:

1. A violin peg comprising a shank formed of metal bent to provide a loop and diverging resilient shank portions, a peg having a head and a tapered shank, the loop and parts of said shank 35 portions being embedded in the said head and in said shank, and a tubular foot piece receiving said shank portions for clamping the shank portions against a violin string.

2. A violin peg having diverging resilient shank 40 portions pointed at the ends, and a tubular foot piece having a tapered guide surface at one end for directing said pointed ends of the shank portions into the tubular foot piece and thereby deforming said shank portions to clamp the end of 45 a violin string between them.

RAYMOND COATES.
